UNITED STATES PATENT OFFICE.

EBENEZER H. ROGERS, JR., OF NEW YORK, N. Y.

TIME-STAMP.

SPECIFICATION forming part of Letters Patent No. 413,328, dated October 22, 1889.

Application filed November 15, 1888. Serial No. 290,892. (No model.)

To all whom it may concern:

Be it known that I, EBENEZER H. ROGERS, Jr., of New York, in the county and State of New York, have invented a new and useful 5 Improvement in Time-Stamp, of which the following is a specification.

I will describe in detail a time-stamp embodying my improvement, and then point out the novel features in claims.

10 In the accompanying drawings, Figure 1 is a vertical section taken on the plane of the line *x x*, Fig. 2. Fig. 2 is a vertical section taken at right angles to Fig. 1 and on the line *y y*, Fig. 1, and looking in the direction 15 of the arrow in Fig. 1. Fig. 3 is a plan or top view of the same, the surrounding case and the hand-stamp being removed. Fig. 4 is a side view of the time mechanism of the stamp, looking in the direction of the arrow of Fig. 20 3. Fig. 5 is a rear view of the time mechanism for the stamp, the case being removed. Figs. 6, 7, 8, 9, 10, and 11 are detail views of the time mechanism of the stamp.

Similar letters of reference designate corresponding parts in all the figures.

25 My improvement involves the use of clock mechanism, which may be of any desirable kind, which clock mechanism transmits motion to a series of indicating-wheels, whereby 30 time may be recorded upon a paper or document when the same is forced against the indicator-wheels. The time indicated will be that of the year, the month, the day, the hour, the minute, and whether the impression is 35 made during a.m. or p.m., the shortest duration of time indicated being that of minutes. Motion to operate the minute-indicating wheel is transmitted directly from the minute-shaft.

40 Referring more particularly to Figs. 2, 3, and 4, A designates a pinion driven from the pinion A' on the minute-shaft of the clock. These pinions are of the same diameter and have the same number of teeth; consequently 45 the pinion A will rotate at the same speed as the minute-shaft of the clock. The pinion A is mounted upon a shaft *a*, journaled in suitable bearings in the main frame B of the time - indicating mechanism for the stamp. 50 Upon the shaft *a* is mounted a ratchet-wheel A², which ratchet-wheel has sixty teeth. Rig-

idly mounted upon a rock-shaft A³, which latter is also journaled in the main frame B, is a lever A⁴. The lever A⁴ bears near its lower extremity a tooth a'. (Shown more 55 clearly in Fig. 9.) The tooth a' is in contact with the teeth upon the ratchet-wheel A². The ratchet-wheel A² rotates in the direction of the arrow shown thereon in Fig. 9; consequently as it rotates the tooth a' will be moved 60 outwardly by the teeth upon the ratchet-wheel successively, causing the lever A⁴ to rock, and causing the rocking of the rock-shaft A³. Upon the outer end of the rock-shaft A³ is a finger a², rigidly secured thereon. Against 65 this finger bears a spring a³, which spring is secured near its lower end in a suitable support made fast to the frame B. The tendency of this spring is to always cause the rocking of the rock-shaft A³ in such manner that the tooth 70 a' of the lever A⁴ will be maintained firmly in contact with the teeth of the ratchet-wheel A². When, therefore, the lever A⁴ has been rocked by the rotation of the wheel A² and the tooth a' moves past one of the teeth on 75 the ratchet-wheel, it will be quickly sprung into the adjacent space between the tooth just passed and the next tooth. The upper arm of the lever A⁴ bears near its extremity a pawl a⁵. This pawl is loosely hung upon the 80 lever. Its outer extremity bears a tooth a⁶, which tooth engages with the teeth upon a ratchet-wheel A⁵. This ratchet-wheel is rigidly secured upon one side of a minute indicator-wheel A⁶. The minute indicator-wheel 85 bears upon its periphery raised figures, extending successively about the periphery, and indicating the minutes from one to sixty. A complete rotation of the minute indicator-wheel occurs each hour. When the ratchet- 90 wheel A⁵ rotates to cause the rocking of the lever A⁴, the pawl a⁵ will be moved along a distance equivalent to the length of a tooth upon the ratchet-wheel A⁵, and when the tooth a' on the lever A⁴ springs into the next notch on 95 the wheel A⁵, through the action of the spring a³, the pawl a⁵ will be moved rearwardly, so that the tooth a⁶ thereon will cause the rotation of the ratchet-wheel A⁵ a distance equivalent to the length of one of the teeth thereon. 100 As there are sixty teeth on the wheel A⁵, and there are sixty impulses given to the lever A⁴

by the wheel A², there will be sixty impulses given to the wheel A⁵ and to the minute indicator-wheel A⁶.

A⁷ indicates a stop-pawl mounted upon a rock-shaft a⁷, journaled in the frame B. Outside the frame said rock-shaft has rigidly secured to it a finger a⁸, actuated by a spring a⁹ in a manner similar to the spring a³. This spring operates to keep a toe a¹⁰ upon the stop-pawl A⁷ in constant contact with the teeth of the ratchet-wheel A⁵. The stop-pawl prevents the reverse rotation of the wheel A⁵ from the direction in which it was rotated by the pawl a⁵.

Upon the shaft a is rigidly mounted a cam b. As shown, this cam is what is known as a "snail-cam." Against the periphery of this cam bears a tooth b' upon one arm of a lever B'. (Shown more clearly in Fig. 8.) The lever B' is rigidly mounted upon a rock-shaft b², journaled in the frame B. Its upper arm has pivotally connected with it a pawl b³, provided with a tooth b⁴. The tooth b⁴ engages teeth upon a ratchet-wheel B², rigidly secured to one side of an hour indicator-wheel B³. The hour indicator-wheel B³ has upon its periphery raised figures indicating twelve hours. The ratchet-wheel B² has twelve teeth. As the shaft a rotates but once each hour, the snail-cam b will consequently be rotated but once in the same period. As the tooth b' of the lever B' bears against the periphery of the cam b, the lever will be gradually rocked during the rotation of the cam until it has moved the pawl b³ and the tooth b⁴ thereon a distance equivalent to the length of one of the teeth on the ratchet-wheel B². At each complete rotation of the cam b the tooth b' on the lever B' will move over the step upon the cam by reason of the action of the spring b⁵ operating upon a finger b⁶, mounted on a rock-shaft b⁷, and acting in the manner previously described for the springs a³ a⁹. When so rocked, the pawl b³ will be retracted, causing the tooth b⁴ to rotate the ratchet-wheel B² a distance equivalent to the length of one of the teeth thereon, thus rotating the hour-wheel a distance equivalent to the distance between two of the raised figures upon its periphery. As the cam b rotates but once each hour, an impulse will be given to the hour-indicator wheel but once each hour.

Co-operating with the ratchet-wheel B² is a stop-pawl B⁴, actuated by a spring b⁷, operating upon an arm b⁸, rigidly secured upon a rock-shaft b⁹ in the manner previously described.

I will now describe the manner in which the days of the month are indicated and also the divisions of each day into a. m. and p. m. Upon the minute-shaft S of the clock, outside the pinion A', is a pinion C. The pinion C gears with a pinion C', mounted upon a stud c extending from the frame of the clock. Upon the stud c, outside the pinion C', is a pinion C², which pinion gears with a pinion C³, which pinion is rigidly mounted upon a

shaft C⁴, journaled in the frame B. Upon the shaft C⁴ are rigidly secured two cams C⁵ C⁶, which rotate with the same. The pinions C, C', C², and C³ are of such diameter that they cause the rotation of the shaft C⁴ once in every twenty-four hours. The cam C⁵ is a snail-cam. Against its periphery bears a tooth c' upon the lower arm of a lever C⁷, mounted upon a rock-shaft C⁸, journaled in suitable bearings in the frame B. This lever is spring-actuated in one direction by a spring c², acting upon an arm c³, rigidly secured upon the rock-shaft C⁸, outside the frame B in the manner previously described. The upper arm of the lever C⁷ has pivotally connected to it a pawl C⁹, which pawl is provided with a tooth c⁴, which pawl engages the teeth upon a ratchet-wheel C¹⁰, which ratchet-wheel is rigidly secured to one side of a day-indicator wheel C¹¹, the periphery of which has formed upon it raised figures indicating the days of the month. The ratchet-wheel C¹⁰ is provided with thirty-one teeth. Each time the snail-cam C⁵ rotates it causes the gradual rocking of the lever C⁷, and causes the movement of the tooth c⁴ upon the pawl C⁹ a distance equivalent to the length of one of the teeth upon the ratchet-wheel C¹⁰, and each time the tooth c' on the lever C⁷ moves off from the step upon the cam the pawl C⁹ is retracted by the spring c², causing the rotation of the ratchet-wheel C¹⁰ a distance equivalent to the length of one of the teeth on said wheel. As there are thirty-one such teeth, thirty-one impulses will be given to said wheel and to the day-indicator wheel each month. If there are less days in the month than thirty-one, the lever C⁷ may be rocked independently of the cam C⁵, to set the day indicator-wheel. This is accomplished by a pin k, secured to the lever C⁷ and extending through a curved slot k' to the outside of the case K.

It is desirable to indicate the division of the day into a. m. and p. m. For this purpose I arrange upon the shaft C⁴ an S-cam, bearing against the periphery of which is a tooth d upon a lever D, mounted upon a rock-shaft D', journaled in the frame B. The lever D is spring-actuated by a spring d', operating upon a finger d² upon the shaft D', outside the frame B, and adapted to hold the lever D in contact with the cam C⁶ in the manner previously described. The upper arm of the lever D bears a pawl D², provided with a tooth d³ engaging the teeth upon a ratchet-wheel D³, rigidly secured to one side of an a. m. and p. m. indicator-wheel D⁴. The indicator-wheel D⁴ is provided upon its periphery with the letters A. M. and P. M. I have shown twelve such combinations of letters and twelve teeth upon the ratchet-wheel D³; but I may use any desired number. Each time the S-cam is rotated it twice rocks the lever D at regular intervals (or, in other words, once every twelve hours) in such manner that the pawl D² will be moved inwardly upon the ratchet-wheel D³ a distance equivalent to the length of one of

said teeth, and each time the tooth d is moved off from a step upon the cain C^6 the lever will be retracted by the spring a' , to cause the rotation of the wheel D^3 a distance equivalent 5 to the length of one of its teeth, thus giving an impulse to the wheel D^4 once every twelve hours.

Co-operating with the ratchet-wheels C^{10} D^3 are stop-pawls D^5 D^6 , mounted upon shafts 10 D^7 D^8 , and actuated by springs D^9 D^{10} , bearing against fingers D^{11} D^{12} , rigidly mounted on the shaft D^7 D^8 . Coacting with each of these levers A^4 , B^4 , C^7 , and D are springs e . These springs are shown as flat, and secured 15 near one of their ends to the said levers, respectively. At their free ends they bear against squared ends of the pawls a^5 , b^3 , C^9 , and D^2 , and serve to maintain such portions in engagement with the teeth upon the ratchet- 20 wheels A^5 , B^2 , C^{10} , and D^3 , respectively. Co-operating with the pawls a^5 , b^3 , C^9 , and D^2 are stops f , which stops consist of pins extending inwardly from the side portions of the frame 25 B and into the path of toes upon the pawls. These stops prevent the pawls from being moved too far in one direction by the respective springs a' , b^5 , c^2 , and d' .

In Fig. 6 I have shown an indicator-wheel G , for indicating the months of the year. 30 Upon the periphery of this wheel are raised letters indicating the twelve months. Upon the wheel G is rigidly secured a toothed wheel G' . Secured upon the frame B is a support g for a spring g' . The spring g' bears upon 35 a stop-pawl g^2 , which stop-pawl is adapted to engage the teeth of the toothed wheel G' . Extending to the outside of the frame B is a shaft g^3 . Upon the inner end of said shaft is a rigidly secured a toe g^4 . The toe g^4 is in contact 40 with the teeth upon the toothed wheel G' . When the shaft g^3 is rotated, the toe g^4 will cause the rotation of the toothed wheel G' a distance equivalent to the distance between two teeth on said wheel, and consequently 45 the rotation of the wheel G a distance equivalent to the distance between any two adjacent months indicated upon the wheel G . I have shown a coil-spring g^5 , abutting at one end against the wheel G and at the other 50 against a collar g^6 , whereby the toe g^4 is maintained in engagement with the wheel G' .

In Fig. 11 I have shown an indicator-wheel for years. Upon this wheel any number of years may be indicated in raised letters. This 55 wheel may be rotated by hand by placing the finger upon the raised figures indicating years upon the periphery of the wheel and moving it circumferentially. In combination with this wheel, which I designate by the letter H , I have shown a toothed wheel H' and a stop-pawl h' , actuated by a spring h^2 .

All the wheels A^6 , B^3 , C^{11} , D^4 , G , and H are mounted upon a single shaft, which shaft passes loosely through them, so that they may 65 be rotated freely thereon. The shaft G^{11} is rigidly secured near its ends in the side portions of the frame B .

In Fig. 3 I have shown more clearly a means for indicating the sort of record the time of filing of which it is desired to record. This record consists of an octagonal or many-sided barrel J , mounted upon a shaft j , journaled in the side portions of the frame B . Upon the outer end of this indicator-barrel is secured a hand-piece j^2 , by which the shaft and the barrel J may be rotated. I prefer that the said hand-wheel be as many-sided as the barrel, and that upon each side of the hand-piece should be delineated a record agreeing with that upon the corresponding side of the barrel when both are uppermost or in a position to be printed upon. Upon the upper side of the printed mechanism and opposite the indicator last described may be arranged the name of a person, firm, or office, as the case may be, for whom the record is being made. This indicator I have designated by the letter J^2 , and the same may be stationary and cast in a top plate J^3 for the indicator. Upon each side of the top plate J^3 are arranged rollers j^3 , over which may be passed an ink-ribbon. A case K contains in this example of my improvement both the clock mechanism and the time-indicator mechanism. Upon the top of the case K and rigidly secured thereto is an arm K^4 , which arm bears near one end an upright tubular portion, through which extends a tube k' , upon the upper end of which is a hand-piece k^2 . Within the tubular portion k' is arranged a coil-spring k^3 . Upon the lower end of the tubular portion is arranged an impression-plate k^4 . The spring k^3 abuts upon one end against the hand-piece k^2 , and at the other end against a screw k^5 , passing through the tubular portion of the arm k and the tube k' . By depressing the hand-piece k^2 the impression-plate k^4 may be pressed downwardly upon the top of the figures or letters appearing upon the indicator-wheels and the coil-spring k^3 and above the inking-ribbon which may be employed. If now a paper or other document be placed between the impression-plate k^4 and the indicators appearing at the top of the indicating mechanism and the hand-piece k^2 be depressed, the time at which the impression was made will be accurately imprinted upon said paper or document. As the indicator-wheels for the minutes, hours, days, &c., are all of the same diameter, the time which it is desired to indicate will be accurately presented at the same time, just above the surface of the plate J^3 , in order to accomplish the imprint referred to.

In order to accomplish the setting of the clock and the time-indicator mechanism at one and the same time, I have shown a shaft L , protruding near one end beyond the case K , which shaft is journaled in the side portions of the frame B . Upon the inner end of this shaft is rigidly mounted a pinion l , which pinion is adapted to engage the pinion A' upon the minute-hand shaft of the clock. This pinion l is not, however, always in en-

gagement with the pinion A'. I desire to keep it normally out of such engagement, and for this purpose I employ a coil-spring l', abutting at one end against one of the side portions of the frame B and at the other against a collar l², rigidly secured to the shaft L. The tendency of this spring is to force the pinion l out of engagement with the pinion A'. By forcing the shaft L inwardly, however, against the resistance of the spring l' the pinion l will be caused to engage the pinion A', when, by rotating the shaft L, the pinion A' may be rotated in such manner as to set the clock properly. As the pinion A' controls the time-indicator mechanism, by rotating the said pinion the time mechanism—or, in other words, the indicator-wheels operated by the clock—is set at the same time as the clock.

20 What I claim as my invention, and desire to secure by Letters Patent, is—

1. In a time-stamp, a series of indicator-wheels, rotatable independently of each other, pivoted levers carrying pawls engaging said indicator-wheels, shafts carrying cams for acting on said levers, and pinions on said shafts, combined with a clock mechanism provided with pinions meshing directly with the pinions of the indicator mechanism, whereby motion is imparted to the shaft-carrying cams and thence through the levers carrying pawls to the indicator-wheels, as set forth.

2. In a time-stamp, the indicator-wheels A⁶, B³, C¹¹, and D⁴, provided with ratchets fast at their sides and rotatable independently on a shaft, pawls engaging said ratchets, and pivoted levers connected to said pawls, shafts a and C⁴, a ratchet-wheel A², and a snail-cam b, and gear A on shaft a, a snail-cam C⁵, an S-cam C⁶, and a gear C⁸ on shaft C⁴, the said ratchet-wheel and cams being arranged to act directly on the pivoted levers, combined with a clock mechanism the minute-shaft of which is provided with pinions A', C, C', and

C², through the latter of which motion is imparted to shaft C⁴, the said clock mechanism being arranged with its pinions A' and C in direct engagement with the pinions A and C', respectively, whereby motion is imparted to the shafts a and C⁴, and thence to the indicator-wheels, substantially as and for the purpose described.

3. In a time-stamp, the indicator-wheels A⁶, B³, C¹¹, and D⁴, provided with ratchets fast at their sides and rotatable independently on a shaft, pawls engaging said ratchets, and pivoted levers connected to said pawls, shafts a and C⁴, a ratchet-wheel A², and a snail-cam b, and gear A on shaft a, a snail-cam C⁵, an S-cam C⁶, and a gear C⁸ on shaft C⁴, the said ratchet-wheel and cams being arranged to act directly on the pivoted levers, combined with a clock mechanism the minute-shaft of which is provided with pinions A' and C and C' C², through the latter of which motion is imparted to shaft C⁴, the said clock mechanism being arranged with its pinions A' and C in direct engagement with the pinions A and C', respectively, whereby motion is imparted to the shafts a and C⁴ and thence to the indicator-wheels, and the indicator-wheel G, with separate means for rotating the same, substantially as and for the purpose described.

4. The combination, with time mechanism, of time-indicator mechanism comprising a day indicator-wheel, and an indicator-wheel for a. m. and p. m., a shaft deriving motion from the time mechanism, a snail-cam for transmitting motion to the day indicator-wheel, and an S-cam for transmitting motion to the a. m. and p. m. indicator-wheels, both said cams being mounted on said shaft, substantially as specified.
